INVENTOR,
Harold C. Scharff

UNITED STATES PATENT OFFICE

HAROLD C. SCHARFF, OF ST. LOUIS, MISSOURI.

ELECTRIC-LIGHTING FIXTURE.

Application filed July 30, 1920. Serial No. 400,177.

To all whom it may concern:

Be it known that I, HAROLD C. SCHARFF, a citizen of the United States, residing at St. Louis, Missouri, have invented a certain 5 new and useful Improvement in Electric Lighting Fixtures, of which the following is a full, clear, and exact description, such as will enable others skilled in the art to which it appertains to make and use the same, 10 reference being had to the accompanying drawings, forming part of this specification.

My invention relates generally to electric lighting fixtures or brackets and more particularly to a universal joint for said brackets or fixtures, the principal object of my invention being to provide a relatively simple 15 form of joint between the post or standard of the fixture and the lamp-carrying arm thereof, of which joint will permit the lamp-carrying arm to be swung into practically any vertical or horizontal angle with respect to the post or standard, thereby permitting the lamp carried by the arm to be positioned immediately adjacent to a machine or point 20 that is to be under constant observation of a workman or attendant.

A further object of my invention is to provide a universal joint for electric light fixtures that is devoid of wires, and which construction greatly simplifies the manufacture and repair of the joint and materially lessens the liability of the parts becoming inoperative as a result of breakage or disarrange- 25

30 ment of wires.

- A still further object of my invention is to provide an electric lighting fixture having a universal joint that is simple, strong and durable, and very effective in performing 35 its intended functions.

With the foregoing and other objects in view, my invention consists in certain new and novel features of construction, arrangement, combination of parts, such as will be 40 hereinafter more fully described and claimed, and illustrated in the accompanying drawing, in which

45 Fig. 1 is a front elevational view of a light fixture of my improved construction, the same being shown in position on a table adjacent to a sewing machine;

50 Fig. 2 is a top plan view of the universal joint contemplated by my invention;

Fig. 3 is a side elevational view of the universal joint; 55

Fig. 4 is a vertical section taken approximately on the line 4—4 of Fig. 3;

Fig. 5 is a vertical section taken approximately on the line 5—5 of Fig. 2;

Fig. 6 is a detailed section of a modified 60 form of the contact members utilized in my improved joint;

Fig. 7 is a plan view of a modified form of the discs made use of in carrying out my invention; 65

Fig. 8 is an elevational view of a modified form of the joint;

Fig. 9 is a top plan view of a further modified form of the joint.

Referring by numerals to the accompanying drawings, which illustrate a practical embodiment of my invention, 10 designates a tubular post or standard which serves as a conduit for the current-carrying wires that pass through the fixture, said wires leading into said post or standard through suitable conduit 11, to which the lower end of the post or standard 10 is connected. 70

Where my improved fixture is utilized on a work table adjacent to machinery or the like, said post or standard extends upwardly through a work table, such as "A," to one side of a machine, such as "B," and thus the lamp-carrying arm forming a part of the fixture may be swung towards and away 80

85 from, and vertically with respect to, said machine. The branch current-carrying wires that lead through the tubular post or standard 10 are designated by *a*, and the same are suitably connected to the said line 90

wires *b* that pass through conduit 11. Removably connected to the upper end of post or standard 10 is a vertically disposed cup-shaped member 12, the cavity or chamber of

95 which is filled with suitable insulation 13, such as fibre, hard rubber, porcelain, or bakelite. The outer face of this body of insulation lies flush with the face of the edge of the annular wall of member 12, and seated in the body of insulation with their 100

outer face also flush with the edge-face of the annular wall of member 12 is a pair of contact rings 14, the same being concentric with each other and with the axis of the member 12. These contact rings are secured 105

100 to the insulation in any suitable manner,

and they are thoroughly insulated from each other. One of the current-carrying wires of the conductor *a* leads to the outer one of these rings, and the other conductor leads to 5 the inner ring. (See dotted lines Fig. 5.)

Lying directly against the face of member 12, is a member 15 that is identical in size and construction with the member 12, and said member 15 is provided with a body 10 16 of suitable insulating material, in the outer face of which is imbedded contact rings 17, the outer faces of which are also flush with the edge-face of the annular wall of member 15 and adapted to make direct 15 contact with the corresponding faces of rings 14 when the two members 12 and 15 are properly assembled. The members 12 and 15 are held in assembled relation by an axially disposed bolt 18 that passes through 20 said members, and the threaded end of said bolt receiving a winged nut 19. Washers 20 are seated beneath the head of this bolt and winged nut in order to assist said parts in holding the members 12 and 15 in clamped 25 engagement. By virtue of this construction, member 15 can be rotated in either direction upon member 12, and the respective members of the pairs of contact rings 14 and 17 will remain in direct electrical contact with each other so as to serve as a path 30 for electric current. Obviously, by tightening winged nut 19 member 15 can be locked after being adjusted on member 12.

Formed integral with the member 15 and 35 disposed at right angles thereto, is a chambered member 21 that is identical in size and construction with the members 12 and 15, and located within the member 21 is a body 22 of suitable insulation, the outer face 40 thereof lying flush with the outer edge of the annular wall of member 21, and seated in the outer portion of this body of insulation are inner and outer contact rings 23, the outer faces of which lie flush with the 45 outer face of the body of insulation 22. These contact rings are retained in position in the body of insulation 22 in any suitable manner, and leading from the annular contact members 17 that are carried in 50 member 15 to said contact rings 23 are suitable conductors 24. (See dotted lines Fig. 3.)

Arranged against the insulated face of member 21 is a member 25 that is identical in form and construction with the members 12, 55 15, and 21, and seated in the chamber of member 25 is a body 26 of insulating material, in the outer face of which is imbedded a pair of concentric contact rings 27. Member 25 is adjustably secured to member 21 60 by means of an axially disposed bolt 28, on the threaded end of which is located a winged nut 29. Secured to the edge of member 25 in any suitable manner is a tubular arm 30, the free end of which carries a 65 socket 31 that is adapted to receive an ordi-

nary electric lamp 32, and if desired, the latter may be provided with a suitable reflector or guard, such as 33. Leading through this tubular arm 30 from the contact members within, socket 31 to the annular contact members 27 are current-carrying wires *c*. 70

When my improved fixture is properly assembled and set up for use, current from the main line wires *b* passes through branch 75 conductors *a* that extend through the tubular post or standard 10, the upper ends of which last mentioned conductors are connected to the contact rings 14. From these contact rings the current passes into and 80 through rings 17 in member 15, and from the latter through the conductors 24 into the contact rings 23 that are positioned in member 21. From these last mentioned contact rings the current passes direct to 85 contact rings 27 in member 25, and from those to and through conductors *c* to lamp 32 that is located in socket 31. By unscrewing winged nut 19 member 15 can be rotated in a vertical plane to adjust the vertical 90 position of member 21, and which latter is fixed to said member 15 and the parts can be secured in their adjusted position by tightening the winged nut 19. By unscrewing winged nut 29 member 25 can be rotated 95 on the under side of member 21 so as to adjust the lateral position of the lamp-carrying arm 30 that is secured to said member 25, and as a result of this vertical and horizontal adjustment the lamp can be shifted 100 into practically any position within the limits of the movable parts of the fixture.

When the winged nuts 19 and 29 are tightened to lock the pairs of ring-containing members in their adjusted positions, the 105 various pairs of contact rings, 13, 17, 23 and 27 will be maintained firmly in contact with each other, and as a result of such contact paths for the current to the lamp carried by arm 30 will be formed.

In Fig. 6 I have shown a modified arrangement of the contact members between a pair of the ring-containing members, and which construction includes a spring-pressed pin 35, which performs the functions of a brush contact, as the member carrying said pin is adjusted with respect to the opposite member in which the contact rings are located. 115

In Fig. 7 I have shown a modified construction wherein the adjacent edges of the annular walls of the co-operating members are provided with notches 36, the same being adapted to inter-engage with each other when said members are properly assembled, thereby decreasing the liability of one member to rotate upon another when properly assembled. 120

In Fig. 8 I have illustrated a form of joint which includes but a single pair of 100

ring-containing members, one of which is carried by the post or standard 10^a, and the other one being adjustably connected to the first mentioned member, and connected to a 5 lamp-carrying arm 30^a.

- In Fig. 9 I have shown a modified construction wherein a pair of double or connected ring-containing members, such as 37, are adjustably mounted upon a single disc 10 38, and the latter being fixed on the upper end of a supporting post or standard, and each of the outer members of the double members having adjustably connected thereto the members that are secured to the inner ends of lamp-carrying arms such as 39. This construction provides for two adjustable arms disposed on opposite sides of a single post or standard.

A lighting fixture of my improved construction is comparatively simple, is capable of being easily and cheaply produced, and is equipped with a universal joint that is devoid of free or loose current-carrying wires, and which construction is effective in 25 minimizing the liability of the structure becoming inoperative as a result of loose or broken wires.

It will be readily understood that minor changes in the size, form and construction 30 of the various parts of my improved light fixture may be made and substituted for those herein shown and described, without departing from the spirit of my invention, the scope of which is set forth in the appended claims.

I claim as my invention:

1. A joint for electric lighting fixtures comprising, in combination, a pair of cooperating oppositely disposed cup-shaped members, a body of insulation disposed within each, and wholly filling the cavities of, said members, a pair of concentric con-

tact rings fixed flatwise in each insulation body, the outer face of each ring being flush with the edge-face of the annular wall of its 45 respective cup-shaped member, and means for adjustably clamping the cup-shaped members together with the rings of one insulation body in sliding electrical engagement with the rings of the other insulation 50 body.

2. A joint for electric lighting fixtures comprising, in combination, a pair of rigidly connected cup-shaped members, the annular wall of one of said members being disposed substantially at right angles to the annular wall of the other member, a third cup-shaped member oppositely disposed to and adapted for co-operation with one of said members, a fourth cup-shaped member 60 oppositely disposed to and adapted for co-operation with the other member of said pair, a body of insulation disposed within each, and wholly filling the cavities of, said respective members, a pair of concentric 65 contact rings fixed flatwise in each insulation body, the outer face of each of said rings being flush with the edge-face of the annular wall of its respective cup-shaped member and the rings of the first pair of 70 cup-shaped members being electrically connected, and means including separate bolts extending axially through each set of oppositely disposed cup-shaped members for separately clamping said sets of members 75 together with the rings thereof in sliding electrical engagement, each set of said oppositely disposed cup-shaped members being selectively adjustable independently of the other.

In testimony whereof I hereunto affix my signature this 27th day of July, 1920.

HAROLD C. SCHARFF.
